UNITED STATES PATENT OFFICE.

GEORGE H. DUFOUR, OF CHICAGO, ILLINOIS, ASSIGNOR TO MARSHALL FIELD & COMPANY, OF CHICAGO, ILLINOIS, A CORPORATION OF ILLINOIS.

FEEDING DEVICE FOR PRESSES.

1,313,474.

Specification of Letters Patent. Patented Aug. 19, 1919.

Application filed May 1, 1919. Serial No. 294,033.

To all whom it may concern:

Be it known that I, GEORGE H. DUFOUR, a citizen of the United States, residing at Chicago, in the county of Cook and State of Illinois, have invented certain new and useful Improvements in Feeding Devices for Presses, of which the following is a specification.

The present invention relates to a device to 10 which cards or other articles to be printed can be conveniently applied, and through which they can, with facility and accuracy, be presented to the printing form of a press, such, for instance, as a die press for relief printing, press for printing from an engraved plate, &c., and the object of the invention is to provide a simple and effective device through which to realize these results.

Accordingly, one feature of the invention 20 consists in providing a portable or easily manipulated carrier, having a holder for the cards, and having arresting or justifying faces through which it is adapted to cooperate with a stop, or stops, located on the press, and adjustable relatively to the printing position so as to insure accurate presentation of the card by the mere act of pushing the carrier against the stops; a subordinate feature incident to this part of the invention 25 consisting in developing the faces in the form of arresting faces and justifying faces, of which the former consist of two intersecting faces adapted to engage a stop in two directions; namely, that in which the card is fed to the press; and a direction at an angle thereto, so that when the stop reaches the intersection of the faces the card will be approximately positioned; and the latter, or justifying face, being elongated in 30 a direction transverse to feeding movement so that it will encounter its stop and normally justify the card with the printing line.

Another feature of the invention consists 45 in providing a plurality of card holders upon the carrier adapted to be successively brought to feeding position by rotating the carrier, and to be presented to the press by merely forcing the carrier against the stops 50 from such feeding position, each card holder having associated with it arresting or justifying faces which adapt it for the manipulation described; a subordinate feature incident to this portion of the invention 55 consisting in having one of the intersect-

ing "arresting" faces for each card holder serve as a "justifying" face for an adjacent card holder, as, for instance, by arranging four card holders upon the carrier at 90° apart, and having the arresting face 60 which extends in the line of the feed for one card holder occupy a position at right angles thereto, and therefore co-operate with the justifying stop before or after the carrier has been rotated to the feeding position. 65

A further feature of the invention consists in having the several card holders so arranged that when one card holder is in feeding position, the others are accessible for the introduction of a new card or withdrawal 70 of a printed card; a subordinate feature incident to this portion of the invention consisting in having the carrier tilting upon its center of rotation in a manner to facilitate introduction or removal of cards to or from 75 the carrier.

The invention will be fully understood upon reference to the accompanying drawings, in which

Figure 1 is a partial view of a die press 80 in connection with which, for purposes of illustration, the present invention will be described.

Fig. 2 is a plan view of the bed of said press with the carrier and stops of the present invention applied thereto. 85

Fig. 3 is an enlarged detail view of the carrier.

Fig. 4 is an edge view of the same; and

Fig. 5 is a section of the same on the line 90 5-5 of Fig. 3.

A represents the form member, and B the platen of a known form of press, such, for instance, as is employed for printing from a die or from an engraved plate, between 95 which form member and platen it is necessary to present with great accuracy the card, or other material, to be printed upon. 1 represents a carrier which is provided with a card holder 2, comprising a clip 2* and 100 two positioning edges 2*, 2*, which accurately locate the card upon the holder when it is introduced to the clip. In definite relation to the card holder 2, the carrier has a pair of arresting faces 3, 4, which intersect and so afford means for positioning the carrier with relation to a stop, such as 5; face 3 being extended in the direction in which the carrier is moved to feed the card to the press, so that by placing the forward end of 110

the face 3 against the stop 5, the carrier can be guided to arresting position, which is reached when face 4 comes against the stop 5. Stop 5 is shiftable, as, for instance, by mounting it upon the slotted rule-arm 5^a, secured by wing nut 5^b, so as to afford both longitudinal and lateral adjustment to it in determining the arresting position.

The carrier is provided with a second face 10 3 which coöperates with a stop 6, similarly adjustable by mounting it upon a slotted rule-arm 6^a secured by wing nut 6^b, said second face 3, when the arresting faces 3, 4, are coacting with the stop 5, extending in a 15 direction transverse to the feed, and thereby serving to accurately determine the angular position of the carrier and insure proper relation between the card and the printing line.

20 The clips 2^a, with positioning edges 2^b, 2^c, are repeated at several different radial positions, upon the carrier 1, preferably at 90° apart, as also are the faces 3 and 4. In connection with each face 3 is an arresting face 4, so that while each face 3 is adapted to serve as a justifying face when it reaches the stop 6, it will have the intersecting face 4 properly associated therewith when it reaches the stop 5. In this way, the carrier is adapted to receive a plurality of cards at different positions upon its perimeter, so that by rotating the carrier, each card may be successively presented to the printing operation, it being merely necessary to with- 35 draw the carrier from the stops, rotate it to present a new card to feeding position, and then slide it inward with the feeding movement until it is positioned by the combined action of the arresting and justifying stops.

40 To facilitate rotation of the carrier 1, it is preferably provided on its under side with a bearing stud or rotating center 7, and upon its upper side with a stem 8. It may also be provided with friction-increasing means, 45 such, for instance, as perforations 9, so that while being grasped by the finger and thumb, the other fingers may rest upon its surface to assist in controlling its movement. Turning bearing 7 raises the carrier some- 50 what from the platen upon which it rests, and adapts it to rock upon said bearing, and depress, upon the platen, the card that is, for the time being, in the printing position, at the same time raising from the platen

55 the card holders that are away from printing position, thereby facilitating the introduction and removal of cards from the latter card holders. In this way, the work is greatly facilitated, particularly when the operative has assistants to introduce and remove cards from the carrier, and the operative who is performing the mechanical part of the work, which readily soils the fingers, need not handle the cards at all. Obviously, 60

65 a plurality of carriers might be employed, to

be loaded and delivered in succession to the pressman, and each being removed and replaced by another as soon as the four impressions have been developed.

While the invention is illustrated particularly in connection with the printing of cards, it is to be understood that a carrier may be adapted, by dimensions or otherwise, to the handling of larger sheets of paper or other objects to be printed upon. It might also, with slight modifications, be adapted to hold other articles to be operated upon, as, for instance, in carrying on punching operations in objects of either paper, metal, or other material.

The term "card" as used herein is to be understood as designating any object of paper or other material, and of any size which it may be desirable to introduce to a press through means of the carrier herein described. Also, in the broader aspect of the invention, the reference to "arresting and justifying faces" is to be interpreted as indicating any faces so related that when encountering a stop or stops they will end the feeding movement and determine the angular adjustment of the carrier relative to the printing line. Thus, justifying face 5, regarded for this part of its function, may act as such when occupying some position other than that on the opposite side, from the arresting faces, of the card holder that is for the time being in feeding position.

I claim:

1. A feeding device for presses comprising a carrier free for manipulation in the feeding direction and free to shift its position in response to arresting means; said carrier having a card holder and arresting faces related thereto, adapted to coöperate with arresting means on a press and thereby determine the relation to the printing line of a card inserted in the holder.

2. A feeding device for presses comprising a carrier free for manipulation in the feeding direction and free to shift its position in response to arresting means; said carrier having a card holder and arresting and justifying faces related thereto, adapted, respectively, to coöperate with stops on a press and thereby determine the relation to the printing line of a card to be inserted in the holder.

3. A feeding device for presses comprising a thin plate-like carrier adapted to lie upon the platen of a press with freedom to respond to manipulation thereover and shift angularly thereon in coacting with positioning means; said carrier having a card holder and faces definitely related thereto through which to position the carrier relatively to a printing line.

4. A feeding device for presses comprising a carrier free for manipulation upon the platen of the press and having a turning

- bearing upon which it can shift its position angularly thereon; said carrier being provided with a card holder and with arresting and justifying faces adapted to cooperate 5 with stops for the purpose of arresting the carrier at the printing position and justifying its relation to the printing line.
5. A feeding device for presses comprising a carrier free for manipulation upon the 10 platen of the press and having a turning bearing upon which it can shift its position angularly thereon; said carrier being provided with a card holder and with arresting and justifying faces adapted to cooperate 15 with stops for the purpose of arresting the carrier at the printing position and justifying its relation to the printing line; said carrier being adapted to tip upon said turning bearing and depress its card holder to bring 20 a card therein upon the sustaining surface of the press.
6. A feeding device for presses comprising a carrier free for manipulation upon the 25 platen of the press; said carrier being provided with a turning bearing upon which it is adapted to shift its position angularly upon the press, and with a plurality of card holders adapted to be presented successively to printing position by such angular shifting; said carrier being also provided with 30 arresting and justifying faces adapted to cooperate with stops upon the press to locate the card holder at the printing position and justify it relatively to the printing line.
- 35 7. A feeding device for presses comprising a carrier free for manipulation upon the platen of the press; said carrier being provided with a turning bearing upon which it is adapted to shift its position angularly upon the press, and with a plurality of card 40 holders adapted to be presented successively to printing position with arresting and justifying faces adapted to cooperate with stops upon the press to locate the card holder at the printing position and justify it relatively to the printing line; said carrier being also adapted to tip upon its turning bearing and by said tipping to depress a card holder at the printing position to bring 45 its card upon the sustaining surface of the press and simultaneously raise other card holders from the surface of the press to facilitate introduction and removal of cards.
- 50 8. A feeding device for presses comprising a carrier free for manipulation upon the platen of the press; said carrier being provided with a turning bearing upon which it is adapted to shift its position angularly upon the press, and with a plurality of card 55 holders adapted to be presented successively to printing position by such angular shifting; said carrier being also provided with arresting and justifying faces adapted to cooperate with stops upon the press to locate the card holder at the printing position and justify it relatively to the printing line; said carrier being adapted to tip upon its turning bearing and by said tipping to depress a card holder at the printing position to bring its card upon the sustaining surface of the press and simultaneously raise other card holders from the surface of the press to facilitate introduction and removal of cards.
- 60 9. A feeding device for presses comprising a carrier free for manipulation upon the platen of the press; said carrier being provided with a turning bearing upon which it is adapted to shift its position angularly upon the press, and with a plurality of card 65 holders adapted to be presented successively to printing position by such angular shifting; said carrier being also provided with arresting and justifying faces adapted to cooperate with stops upon the press to locate the card holder at the printing position and justify it relatively to the printing line; the arresting and justifying faces for each card holder being located on opposite sides thereof.
- 70 9. A feeding device for presses comprising a carrier free for manipulation upon the press and for rotation thereon; said carrier having a plurality of card holders adapted to be presented to feeding position by rotation of the card holder, and having 75 upon one side of each card holder a pair of intersecting faces for arresting the carrier, and upon the other side thereof a justifying face.
- 80 10. A feeding device for presses comprising a carrier free for manipulation upon the press and for rotation thereon; said carrier having a plurality of card holders adapted to be presented to feeding position by rotation of the card holder, and having 85 upon one side of each card holder a pair of intersecting faces for arresting the carrier, and upon the other side thereof a justifying face; one of the arresting faces for a card holder constituting the justifying 90 face for an adjacent card holder.
- 85 11. A feeding device for presses comprising a carrier free for manipulation upon the press and for rotation thereon; said carrier having a plurality of card holders adapted to be presented to feeding position by rotation of the card holder, and having 95 upon one side of each card holder a pair of intersecting faces for arresting the carrier, and upon the other side thereof a justifying face; one of the intersecting arresting faces extending substantially in the line of feeding movement, and the justifying face extending at a substantial angle to the direction of feeding movement.
- 100 12. A feeding device for presses comprising a carrier having a plurality of card holders arranged thereon in different radial positions at substantially 90° apart; said carrier being rotatable to present said card 105 holders successively to a printing position and having for each card holder arresting and justifying faces, of which the former comprise each a face extending parallel to the radius of position of the card holder together with a face intersecting the same, and the latter comprises each a face perpendicular to the radius of position of the card holder.
- 110 13. In a feeding device for presses, a rotatable carrier having a plurality of card holders arranged in different radial positions thereon, each card holder having two edges adapted to receive the edges of a card and determine its position relatively to the 115 card holder, and said carrier having in relation to each card holder arresting and justifying faces adapted to cooperate with stops upon a press.
- 120 14. In a press, the combination of a bed, 125
- 130

arresting and justifying stops carried by the press, and a carrier having a card holder with arresting and justifying faces related thereto, adapted to coöperate with the stops upon the press.

15. In a press, the combination of a bed, arresting and justifying stops carried by the press, and a carrier having a card holder with arresting and justifying faces related thereto.

Copies of this patent may be obtained for five cents each, by addressing the "Commissioner of Patents, Washington, D. C."

to, adapted to coöperate with the stops upon the press; said stops comprising abutting members, slotted rule-arms carrying said members, and securing means coöperating with the slots of said arms to adjustably secure them.

15

Signed at Chicago, Illinois, this 28th day of April, 1919.

GEORGE H. DUFOUR.
